ELECTRIC SWITCH.

Application filed November 4, 1924. Serial No. 747,813.

My invention relates to electric switches, and particularly to a snap switch mechanism. The object of my invention is to provide a simple and efficient mechanism of 5 push bar type adaptable to various electrical appliances.

In the accompanying drawings—

Fig. 1 is a section on the line 1—1, Fig. 2, of an electric lamp socket provided with 10 a switch in which my invention is embodied in one form;

Fig. 2 is a section on the line 2—2, Fig. 1;

Fig. 3 is a view similar to Fig. 2, but 15 showing the mechanism in a partly actuated position; and

Fig. 4 is a section on the line 4—4, Fig. 3.

For the sake of illustration I have shown my improved mechanism in an electric lamp 20 socket, but it will be readily understood that it may be embodied in a fitting of any appropriate type, with such appropriate modification as will readily occur to those skilled in the art.

25 The insulating body of the lamp socket illustrated comprises a button 5 or of porcelain or the like, against one end of which is arranged an insulating disk 6 of fiber, paper or other suitable material. The screw shell 30 and center contact terminals, 7 and 8 of the socket, rest against the disk 6. The base flange of the screw shell 7 is engaged beneath the offset extension 9 of the wire terminal 10 and is tapped to receive the screw bolt 11, which passes through the insulating button 5 and disk 6, thus holding the parts rigidly assembled. A second screw bolt 12 diametrically opposite the bolt 11 similarly passes through the button 5 and 35 disk 6 and takes into a washer (not shown) which overlies the screw shell flange in a manner well understood in the art.

Integral with the center contact 8, which is riveted to the disk 6 at 13, is an offset 40 flange 14 which passes through the disk into the switch chamber 15, where it lies against one of the side walls 16 thereof, and forms one of the switch contacts. The other 45 switch contact 17 lies against the same wall of the switch chamber and is integral with the wire terminal 18 which is riveted at 19 to the disk 6. The circuit is made or broken 50 between the switch contacts 14—17 by the switch bar 20, which, in circuit-closing posi-

tion, lies against and bridges the switch contacts, but moves across the switch chamber 15 and lies against the opposite wall 21 thereof in open-circuit position.

The throw of the switch bar is effected by the reciprocation of the push plate 22 arranged in a plane normal to that of the switch bar and guided in slots 23 opening through the opposite sides of the chamber. Moving with the push plate, but preferably having an independent rocking motion with 60 respect thereto, is a double cam member 24, the cam surfaces 25 of which have a sliding engagement in the notch 26 formed in the lower margin of the switch bar 20. In the form here shown, the opposite ends of 70 the push plate 22 are united by an integral web 27 lying at right angles to the plane of the push plate ends and apertured at 28 to accommodate the stem 29 of the cam member 24. The end of the stem 29 is 75 loosely engaged in the well 30 which opens to the switch chamber 15, so that the cam member is free to rock when the push plate 22 is longitudinally displaced. Surrounding the stem 29 is a coil spring 31 which 80 abuts at one end against the web 27 of the push plate, while its other end is engaged in any suitable way by the switch bar 20. For this purpose the bar is provided with a pair of legs 32 which straddle the cam member 24 and web 27 of the push plate (see 85 Fig. 4), and are offset at their lower ends to form hook-like foot pieces 33 which lie on opposite sides of the stem 29 and engage the opposite end of the spring 31. In assembled position the switch bar 20 places 90 the spring 31 under stress, and through its engagement with the cam surfaces 25 maintains the head of the cam member 24 seated against the push plate web 27 while the stem 29 is maintained in the well 30. Inasmuch 95 as the dimensions of the head of the cam member 24 are such that the switch bar 20 rests upon the inclines 25 in its opposite extreme positions, the parts are constantly maintained in properly assembled relation. 100

The push plate is provided with lugs 34 and 35 which work on ledges 36 and 37, the inner ends of which form stops limiting the longitudinal play of the push plate. The foot pieces are held to the ledges 36 and 37 105 by the legs 38 and 39, which extend in the opposite direction and have a sliding en-

gagement with the disk 6. Insulating buttons 40 at opposite ends of the push plate afford means for manual operation of the latter, while bays 41 between the guide slots 23 and main switch chamber 15 accommodate the push plate web 27 and cam 24 in their extreme positions.

The operation of the mechanism is readily understood. Assuming the switch to be in the closed position shown in Fig. 1, the switch bar 20 rests against and bridges the switch contacts 14—17. The thrust of the spring 31 against the incline of the cam 24 through the switch bar, causes the cam member to tilt to the position shown in Fig. 2. If the push plate be now displaced to the right (Figs. 2 and 3) the engagement of the stem 29 of the cam in the hole of the push plate web 27, causes the cam to rock 20 toward the switch contacts 14—17. Inasmuch as the switch bar is detained against movement in the same direction, by reason of its engagement with the contacts, it is forced to ride up the incline of the cam, sliding along the faces of the switch contacts, and simultaneously placing the switch spring 31 under greater stress. As the crest of the cam is rocked past its point of engagement with the switch bar, the stress of the spring 31 causes the switch bar to run down the opposite cam incline, throwing the switch bar away from the switch contacts 14—17 and against the wall 21 of the switch chamber, thus opening the switch. A reversal of the movement of the push plate reverses the throw of the switch bar and again closes the switch.

While I have shown the cam member 24 independent of the push plate, it will be recognized that it may be formed integral therewith, although I prefer the independent construction inasmuch as the rocking of the cam reduces the necessary play of the push plate to effect the throw of the switch bar. Moreover, the lever effect of the cam member renders the action of the switch easier. It will be noted that all of the moving parts of the mechanism are formed of sheet metal which may be readily blanked 50 to the desired shape. The assembly operation is extremely simple, while the movement causes a wide double break capable of handling with safety the current commonly supplied for lighting and other household or office purposes.

With the understanding that various modifications in shape and arrangement of parts may be made while still embodying what I claim as my invention,—

60 I claim—

1. An electric switch mechanism comprising a reciprocating push bar, a V-cam mov-

ing therewith, a spring abutting at one end against and moving with the push bar but extending in the opposite direction from the cam, a floating switch bar riding the cam and operatively connected with the other end of the spring, and means detaining the switch bar against movement with the push bar, to cause the displacement of said switch bar by an incline of the cam and the simultaneous stressing of the spring, followed by the throw of the switch bar down the opposite incline of the cam under the stress of the spring as the crest of the cam passes its point of engagement with the switch bar.

2. An electric switch comprising a reciprocating push bar, a V-cam having a stem passing through the push bar, a coil spring surrounding the said stem, with one end abutting the push bar, a switch bar riding the cam inclines and having legs which straddle the stem and engage the other end of the spring.

3. An electric switch comprising a reciprocating push bar, a V-cam having a stem passing through the push bar, a coil spring surrounding the said stem, with one end abutting the push bar, a switch bar riding the cam inclines and having legs which straddle the push bar and stem and engage the other end of the spring.

4. An electric switch comprising an insulating body recessed to afford a switch chamber and well opening thereto, a reciprocating push bar traversing the switch chamber, a V-cam having a stem fulcrumed in the well and engaged by the push bar, a switch bar riding the cam and a spring holding the switch bar to the cam inclines.

5. An electric switch comprising a reciprocating push bar, a V-cam arranged at one side of the push bar and having a stem projecting beyond the opposite side of the push bar, a spring surrounding said stem and bearing at one end against the push bar with which said end moves, together with a floating switch bar riding the cam inclines and operatively engaging the opposite end of the spring and stressed by the latter against the inclines of the cam.

6. An electric switch comprising a reciprocating push bar, a coil spring abutting at one end against one face of the push bar and moving with said push bar, a V-cam at the other side of the push bar and actuated by said push bar, in combination with a floating switch bar stressed by the other end of the coil spring against the inclines of the V-cam and adapted to ride those inclines.

In testimony whereof I have signed my name to this specification.

OSCAR HAMMERSTROM.
